Patented Sept. 11, 1928.

UNITED STATES PATENT OFFICE.

MAX SCHACHTER, OF NEW YORK, N. Y.

ADJUSTABLE-LENGTH TIE.

Application filed March 26, 1927. Serial No. 178,522.

This invention relates to neckties or scarfs either of the bow or four-in-hand type and has particular reference to adjustably connecting two sections of a tie whereby its 5 length may be varied to a desired size.

One of the objects of my invention is to provide a necktie consisting of two interconnected neck band sections including provision for sliding one section within the other 10 and locking the same whereby the length of the tie may be varied.

A further object of my invention is to provide an adjustable necktie consisting of two sections of the same or different lengths, the 15 ends of said sections being interconnected and fastened together in any desired adjustable position by means of a clip or any other suitable fastening means such as a buckle for instance.

20 To enable others skilled in the art to more fully comprehend and understand the underlying features of my invention that the same may be embodied in the various modifications contemplated, reference is had to the 25 accompanying drawings showing a preferred form of my invention, in which

Fig. 1 is a view showing a conventional type of necktie embodying my invention.

Fig. 2 is a view showing an open loop 30 formed at one end of one of the sections.

Fig. 3 is a view showing a pocket formed in the end of the opposite section and taken on the line 3—3 of Fig. 5.

Fig. 4 is a sectional view showing the open 35 loop formed in one end of one of the sections.

Fig. 5 is a side view of the end of one of the sections.

Fig. 6 is a sectional view showing the interconnected ends of the tie sections.

40 Fig. 7 is a view of a fastening clip for retaining the connected sections when assembled.

Referring now to the drawings wherein like reference characters designate corresponding parts throughout the several views 45 5 designates the wings and 6 the neck band portions of two sections of a tie either of the bow or four-in-hand type. One end of the neck band section 6 is equipped with an open end loop 7. The opposite end of the complementary band 6^a is equipped with an open pocket 8, formed by folding back and stitching the extremity of the neckband section 6 to the portion 9. The pocket 8 is 50 55 adapted to receive the end of a lead pencil or other instrument whereby the end of the

band may be projected into the loop 7 to any desired distance preliminary to fastening the ends of the tie together as shown by Fig. 6.

The preferred fastening means shown and 60 employed consists of an inverted U-shaped clip 10 which is bent downwardly and upwardly as at 11 terminating in the eyes 12. The clip is preferably made of wire such as 65 employed in making paper fasteners for instance and is of sufficient resiliency to clamp and lock the two ends of the tie together.

Referring now to Fig. 6, it will be noted that the thickness of the pocket on the end 9 of one section is sufficient to prevent the end 70 sections of the tie from becoming separated incident to the slight pull which may be necessary in adjusting the neck band sections of the tie before the bow, for instance is made.

Particular attention is directed to the 75 pocket formed in the end of one of the sections which constitutes the most efficient as well as the most simple manner of sliding one end of the band within the complementary 80 opposite end preliminary to securing the clip 85 thereon. I prefer to use a clip such as shown in Fig. 7 because the thickness of the wire is not sufficient to prevent the adjusting of the connected sections of the tie nor does it interfere with the turn-over type of collar.

While I have shown and described my invention with some degree of particularity I realize that various changes in the details of various constructions may be made. I further do not desire to be limited and restricted 90 to the exact details but reserve the right to make such changes as may fairly fall within the scope of the subject matter now being claimed.

Having shown and described my invention 95 what I claim as new and desire to secure by Letters Patent is:

An adjustable tie comprising two separable sections, one of said sections having an open loop at one end and the corresponding 100 end of the second section being overlapped on itself and provided with an open pocket adapted to receive the end of a pointed instrument therein whereby it may be inserted with said instrument within the open loop of the 105 first mentioned section for adjustment relative thereto and a separable, outside fastening element for connecting the two interconnected sections when adjusted.

In testimony whereof I affix my signature.

MAX SCHACHTER.
